Atty's

UNITED STATES PATENT OFFICE

CHARLES WHITNEY STEVENS, OF CHICAGO, ILLINOIS

CASTER BASE

Application filed December 12, 1928. Serial No. 325,459.

This invention relates to a caster base, that is, a small, compact, unitary device adapted to be placed under the individual legs or supports of musical instruments, chiefly pianos, 5 radios, and the like, or in analogous relations, to prevent the passage therethrough of sound-causing vibrations and consequent disturbance in adjacent rooms.

In the accompanying drawings, Fig. 1 is a 10 vertical cross-section through the center of a caster base embodying the invention;

Fig. 2 is a plan view thereof; and

Fig. 3 is a vertical central section of a similar device but with the casing made of metal 15 instead of wood.

Referring to Fig. 1, a small cylindrical casing 10 of wood or other material, formed with any desired ornamental exterior, is provided with a bottom plate 11 of metal or 20 other desired material, secured thereto by any suitable number of screws. A layer preferably of felt cloth 12 is secured, as by gluing, to the bottom surface of the plate 11.

Within the casing there is a bottom disc- 25 like layer 13 preferably of cork, or other elastic or resilient material of substantial thickness; a layer 14 of felt, preferably cattle-hair felt, or other resilient material, which is cup-shaped to extend up along the 30 inside of the casing 10, and on top of this layer is a circular block preferably of wood 15 which fits circumferentially within the upturned flange or edge portion of the layer 14.

A ring 16, which may be of metal, is se- 35 cured by screws to the upper edge of the casing ring 10 and overhangs the outer edge of the wood block 15, whereby all interior parts are confined and held within the casing even when the device is not in use and the felt 40 layer is not compressed.

The upper face of the top block 15 is 45 formed with a depression to receive the leg or support 17 of the piano or other musical instrument, and may be made to conform to the cross-section form thereof, such as round or square, for example. The depression prevents the leg or support when properly in position from physically contacting with the metal ring 16 and the transmission of vibrations directly from the leg to the casing and

thence to the floor, and also assists in holding the caster base in place if the instrument is slid along the floor.

The weight imposed on the block 15, or the proportions of the materials comprising the 55 several layers, should be such that when in use the edge of the block 15 is depressed below and does not touch the ring 16, thereby to prevent passage of the vibrations direct to the casing.

In this construction the piano floats on the blocks 15 and the sound-causing vibrations which travel down the legs encounter first the block 15, next the layer 14, and then the 65 layer 13. These materials of different densities and having different capacities for dissipating, destroying and preventing the passage of the sound-producing vibrations, eff- 70 ectually stop the same, the hair felt pre- sumably having the greatest effect in this re- 75 gard, and the disturbing noises from this cause in the room below or adjacent thereto are thus prevented.

The form shown in Fig. 3 is similar. The casing 10a is metal, preferably sheet metal, and of ornamental outline, with an integral upper ledge 16a. The bottom plate 11 is se- 80 cured by rivets or other desired manner to the outwardly extending flange of casing 10a and is covered by the felt cloth layer 12. Con- 85 tained within the casing 10a is the disc 13, the cup 14 and the block 15a, preferably of wood, fitting within said cup, all of these being inserted in the casing from the bottom.

The depression in the upper side of the 85 block 15a is preferably of such form as to receive and circumferentially fit the caster 18 in the leg 17a of the piano or other instrument.

The operation of the device and its effects 90 in preventing the passage therethrough of sound-causing vibrations is the same as that explained with reference to Figs 1. and 2.

This caster base performs, of course, the 95 usual function of such devices in providing a larger area than the caster or leg itself of the instrument for bearing upon the carpet or rug.

I claim:

1. A caster base comprising a rigid casing, 100

and material within said casing in the path of sound-causing vibrations tending to pass through said base, said material having the capacity of dissipating, absorbing or obstructing the passage of said vibrations, said casing having an inwardly projecting edge portion overhanging the said material and confining the same within the casing.

2. A caster base comprising a rigid casing, and a relatively thick layer of material within said casing on which the weight is imposed in use without contact with the casing, said material having the capacity of absorbing, dissipating or obstructing the passage of sound-causing vibration.

3. A caster base comprising a casing, a filling for said casing for receiving and carrying the weight imposed on the base, said filling comprising a substantial thickness of hair felt.

4. A caster base comprising a casing, layers of different sound-vibration absorbing, dissipating or obstructing materials therein on which the weight carried by the base is imposed, said materials having different capacities for absorbing, dissipating or obstructing the passage of sound vibration, and means for preventing contact of said weight with the casing.

5. A caster base comprising a casing, layers of different sound-vibration absorbing or dissipating materials therein, said materials including a substantial thickness of hair felt, and means for preventing contact of the weight carried by said materials with the casing.

6. A caster base comprising a casing, layers of different sound-vibration absorbing or dissipating materials therein, a block in the casing carried by said materials and entirely surrounded on the sides by one of said layers.

7. A caster base comprising a casing, a filling therefor comprising a layer of material compressible under the weight imposed on the base, and a covering layer of relatively incompressible material to receive the caster, leg or support of the vibration-producing instrument, said casing and said covering layer co-operating to keep the cover in place when the base is not in use and out of contact with each other when the load is imposed on the base.

8. A caster base comprising a casing, sound-vibration dissipating, absorbing or obstructing material in said casing, a cover plate in the casing out of contact with the side walls thereof to receive the caster leg or support of the vibration-producing instrument, and an inwardly projecting flange or ledge on the casing overhanging the periphery of the cover plate and out of contact therewith when the load is imposed on said cover plate.

9. A caster base comprising a circular casing, a layer of resilient material in the bot-

tom of the casing, a cup-shaped layer of hair felt on top of the resilient material, and a wooden block or disc seated within said felt cup, said wooden block or disc being out of contact with the casing when the load is imposed on said block or disc.

10. A caster base comprising a metal casing, a lining of cattle-hair felt in said casing and a rigid block or plate seated in the casing and separated from contact with the sides and bottom of said casing by said lining, said block or plate being out of contact with the upper part of said casing when the load intended to be carried by said caster base is imposed on said block or plate.

11. A caster base comprising a sheet metal casing having an inwardly extending rim flange at its top edge, a filling of sound-vibration dampening material, a solid member peripherally embedded in and floating on said material, said member and material being normally confined within the casing by said flange, said member being out of contact with said flange when the load is imposed thereon in the use of the device, said casing having a bottom opening to permit the insertion of said lining and member in the casing, and a bottom plate secured to said casing and closing said opening.

12. A caster base comprising an annular casing having an ornamental outer surface configuration, a filling of sound-vibration dampening material, a floating supporting member within the casing to receive the leg or supporting member of the vibration-causing instrument, said casing having an inwardly projecting flange at its upper edge extending over said supporting member and a bottom plate secured to said annular casing.

13. A caster base comprising an annular casing member, a sound-vibration dampening filling within said member, a solid supporting member peripherally embedded in and floating on said filling, a cover plate for said casing member detachably secured to said member and having a central opening for the passage without contact therewith of the leg or foot of the instrument supported by the caster base, and a bottom plate peripherally secured to said casing member.

In witness whereof I have hereunto subscribed my name.

CHARLES WHITNEY STEVENS.

CERTIFICATE OF CORRECTION.

Patent No. 1,848,501.

Granted March 8, 1932, to

CHARLES WHITNEY STEVENS.

It is hereby certified that error appears in the printed specification of the above numbered patent requiring correction as follows: Page 1, line 67, before the word "destroying" insert the word absorbing; page 2, line 31, claim 5, for the misspelled word "differnt" read different; and that the said Letters Patent should be read with these corrections therein that the same may conform to the record of the case in the Patent Office.

Signed and sealed this 17th day of May, A. D. 1932.
